Primary Examiner — Robert Delehanty

(74) *Attorney, Agent, or Firm* — Fulbright & Jaworski LLP

(57) **CLAIM**

The ornamental design for faucets, as shown and described.

DESCRIPTION

FIG. 1 is a rear perspective view of a first embodiment of my design comprising a faucet, such as, for example, for use with a sink;

FIG. 2 is a front orthogonal view of the first embodiment;
FIG. 3 is a rear orthogonal view of the first embodiment;
FIG. 4 is a side orthogonal view of the first embodiment;
FIG. 5 is an opposite side orthogonal view of the first embodiment;

FIG. 6 is a top orthogonal view of the first embodiment;
FIG. 7 is a bottom orthogonal view of the first embodiment;
FIG. 8 is a front perspective view of a second embodiment of my design comprising a faucet, the primary difference between the second embodiment and the first embodiment being that the handle of the second embodiment faces toward the mouth of the faucet;

FIG. 9 is a rear orthogonal view of the second embodiment;
FIG. 10 is a front orthogonal view of the second embodiment;
FIG. 11 is a side orthogonal view of the second embodiment;
FIG. 12 is an opposite side orthogonal view of the second embodiment;

FIG. 13 is top orthogonal view of the second embodiment;
and,

FIG. 14 is a bottom orthogonal view of the second embodiment.

The dashed lines in FIGS. 1-14 represent environmental structure and form no part of the claimed design. Specifically, the environmental structure in FIGS. 1-5, 7, 8-12, and 14 represents an example of a connection portion for connecting the first embodiment to a water source and a counter or sink, and an example of a screw (FIGS. 3 and 10) that may be included in the first embodiment.

All other surface(s) or portion(s) of the embodiments of my design not shown in the figures or otherwise described in the specification form no part of the claimed design.

1 Claim, 12 Drawing Sheets
